AQUATIC VEHICLE

Filed Aug. 31, 1929

UNITED STATES PATENT OFFICE

JEAN REHBOCK, OF WASHINGTON, DISTRICT OF COLUMBIA

AQUATIC VEHICLE

Application filed August 31, 1929, Serial No. 389,824, and in France September 19, 1928.

This invention relates to aquatic craft and more particularly to such a device designed to rest lightly upon the surface of the water and to be propelled at a high speed on said

surface.

It has for its object the provision of means for sustaining the craft on the water which, while insuring to it all the buoyancy desirable when at rest, opposes a minimum of resistance to the forward movement of the craft on the water. A further object of the invention is to combine with a craft of this kind which lightly rests upon the water, a propelling means.

Like reference numerals indicate like parts throughout the several figures of the drawings in which:

Fig. 1 is the side elevation of the embodied invention,

Fig. 2 is a plan,

Fig. 3 is the front elevation of a modified form of the invention, and

Fig. 4 is an elevation thereof.

The invention may be embodied in a multiplicity of devices, some of which may be sea-going craft and others small enough to be used as pleasure craft upon inland lakes, the underlying thought, however, being the fact that it is for use in connection with

rough water.

In the drawings the numeral 10 represents the body of an aquatic craft while 11 and 12 represent ariel propellers for driving the craft. The body is mounted in a sustaining frame shown as comprising side beams 13 and 14 at the ends of which are mounted buoyant rollers 15 and 16. Between the ends the body is supported pivotally upon an axle 17 and to either side of the body are additional buoyant rollers 18 and 19.

While a sustaining system of conventional elements is shown it will be appreciated that this system may be formed of other elements and arranged in a different manner. The important point is that the craft is constituted by a body which is swingingly or pivotally mounted in a supporting or sustaining frame and that the body is provided with propelling means either ariel or marine while the supporting system is designed to main-

tain the craft properly buoyed while at rest but which will be substantially lifted onto the surface of the water when the craft is being propelled.

The same principles are shown embodied in an airplane in Figures 3 and 4 in which the numeral 20 represents the fuselage, 21 and 22 the wings, 23 the propeller, and 24 the rudder. The sustaining means in this instance is a single roller 25 at the front of the plane on which the plane is journaled through the legs 26 and 26. The rear roller 27 is utilized to support the plane at rest so that the propeller will not touch either the ground or the water while it is at rest. The numeral 28 represents pneumatic tires which are provided in order that the plane may be driven into a hanger or run along the earth. It will be appreciated, however, that while the plane is traveling over the surface of the water the roller 27 occupies at all times an elevated position about the water.

The operation of both forms will be understood from a description of the operation of the plane in Figure 4. When the craft is at rest the forward roller 25 rests in the water in substantially the depth indicated by the dotted lines in said figure. The line A—A in said figure represents the general level of the water. The full line B—B in that figure represents the plane as it rides the wave and it will be appreciated that as the craft is in motion the roller 25 will be lifted from the water so that only its surface will be in contact with the surface of the water. In fact, due to the revolving of the roller there is a suction of air under the roller between it and the surface of the water as represented by the arrowed lines 29 and this body or film of air will act somewhat as a lubricant reducing the friction between the roller and the water to a minimum.

It will be appreciated that by this arrangement of buoyant element and craft body that the craft is always in a correct line for driving; that it may be lifted or lowered by the water but will never be out of line for correct driving. It reduces to a minimum the displacement or the throwing of water. The effect differs from that produced in the or-

dinary glider plane where the buoyancy is maintained by virtue of the inclination of the support to the plane of the water.

The "aquatic wheels" 15, 16 and 25 may be formed in a number of ways and of a variety of materials. Their surface may be smooth or they may carry rough elements to promote the rolling motion. They may be made hollow and if desired divided into air-tight compartments and they may be filled with cork or similar substance. If they are hollow they may be utilized as reservoirs for fuel, communication with them being through the axle. Their number and disposition on a given craft may vary and will necessarily vary according to the different types of craft. They may be even grouped and mounted in the form of rigid trains or flexible caterpillars, or they may be formed in trains and coupled or not, as desired.

In my prior French and German applications for patents referred to in the oath to this application the rollers have been shown in the form of spheres, cylinders, barrel-shaped, double cones, etc.

What is claimed is:

1. In an aquatic craft, a craft body, a buoyancy system in which said craft body is swingingly mounted, said system comprising rollers revolvably mounted herein and designed to contact in the movement of the craft with the surface of the water and to cause a film of air to be entrapped between them and the water surface, and means independent of the buoyancy system for propelling the craft at a high speed over the surface of the water.
2. In an aquatic craft, a craft body, a buoyancy system in which said craft body is swingingly mounted, a driving means for said body, the system comprising elements which are movable under the influence of the water surface, said movement being free of any movement of the body or driving means.

In testimony whereof I affix my signature.

JEAN REHBOCK.
